UNITED STATES PATENT OFFICE.

ERIC ANDERSON, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

DOOR-SWITCH.

1,031,611.

Specification of Letters Patent.

Patented July 2, 1912.

Application filed August 19, 1911. Serial No. 344,942.

To all whom it may concern:

Be it known that I, ERIC ANDERSON, a citizen of the United States of America, and residing at Bridgeport, in the county of 5 Fairfield and State of Connecticut have invented a certain new and useful Improvement in Door-Switches, of which the following is a specification.

My invention relates to electric door switches and the object of my invention is to provide a simple and efficient operating mechanism possessing certain novel features hereinafter described and illustrated by way 10 of example, in the accompanying drawing 15 in which,

Figure 1 is a vertical section through the switch casing showing, partially broken away, a switch mechanism embodying my invention in one form; Fig. 2 is a similar 20 view with the switch parts in another position; Fig. 3 is a vertical section on the line 3—3 Fig. 5; Fig. 4 is a horizontal section on the line 4—4, Fig. 1; Fig. 5 is a vertical section on the line 5—5, Fig. 1; and 25 Fig. 6 is an end elevation of the switch.

In switches of the present character it is highly desirable that the contact may be made and broken by a short stroke of the actuating plunger, so that the device may 30 be actuated by the door whether or not the latter accurately fits its frame. A switch mechanism of this character is operative not only when the door is first installed and properly fits the frame, but also after the 35 same has dried out and somewhat shrunk from its original size leaving a greater space between the frame and the actuating stile of the door than existed at the time the door was installed. To this end I provide 40 a switch operating mechanism with plunger member, the connections from the latter to the escapement being such that the initial inward and the final outward travel of the plunger serve to operate the switch, while 45 at the same time the connection of the plunger to the escapement mechanism is such that the plunger is free to travel inward until it is flush with the face plate thus permitting the door to be closed when the stile 50 is flush with the frame.

In the embodiment of my invention illustrated, the switch comprises a metallic casing 10 provided with a face plate 11, through which projects an actuating latch 12, pivoted at 13 to the casing. The base of 55 the casing is apertured at one end 14 to permit the passage therethrough of an offset 15, of an insulating block 16, carrying switch terminals 17 and connections therefrom to the binding screws 18. Securing 60 screws 19 passing through a shoulder of the insulating block are screwed into threaded holes in the base 20.

The switch mechanism is carried upon a frame plate 21 of heavy sheet metal offset at 65 the bottom to form a securing flange 22, and at the top to form a guide flange 23. Securing screws 24 pass through the flange 22 into the base 20 of the casing. The switch lever 25 is pivoted at 26, to the frame 21, 70 and the switch blades 27 are carried by the arm 28, which is offset at its upper end to form a detent engaging flange 29. At right angles to the arm 28, a second arm 30 is formed, the free end of which travels between the stops 31, formed upon a lateral extension of the frame plate. The rocking lever 32 is also pivoted upon the spindle 26, and is offset at one end to form a spring engaging finger 33, the opposite sides of which 75 and of the switch arm 30, the free ends of usual actuating spring 34 engage. The other end of the rock lever is provided with an angled slot 35, in which the pin 36, of the push plate 37, engages. The latter is guided 80 rectilinearly by the lug 38 struck up from the back of the frame. A detent 39 on the push plate 37 is angled forward into the path of the flange 39 on the upper end of the switch lever. The flange 40 at the upper 90 end of the push plate engages and is preferably sweated to the plunger 41, and takes its downward motion from the latter, while it is returned to position by the coil spring 42 which surrounds the plunger stem. The 95 upper end of the latter is forked to receive the pivoted trigger 43, the free end of which rests in the angle 44 of the latch 12 and serves to transmit the inward motion of the latter to the plunger without undue friction 100

upon the latch. A socket 45 below the plunger receives the stem of the latter and aids the guide lug 38 in rectilinearly guiding the push plate and plunger.

5 The operation of the mechanism is readily understood. Assuming the door be closed, and the latch 12 depressed to its full extent, the mechanism takes the "off" position shown in Fig. 2. As will be noted, the pin 10 36 on the push plate is now near the bottom of the angled slot 35, while the detent 39 is out of engagement with the flange 29 on the switch lever. As the latch moves out on the opening of the door, the return spring 15 42 presses the plunger 41 up, carrying with it the push plate 37 and detent 39. When the pin 36 has risen to the angle of the slot 35, the rock lever rotates under the action of the spring 34, until the free end of the 20 latter engaged by the rock lever comes into contact with the lug 30 of the switch lever. The latter is now subjected to the return action of the spring, but is held temporarily in position by the detent 39, which has risen 25 to position to be engaged by the flange 29 on the switch lever. During the travel of the detent past the flange 29, the rock lever continues its travel thereby putting the switch spring 34 under tension in the opposite direction, so that upon the escape of the flange 30 29 from the detent 39, the switch arm snaps into engagement with the switch terminals, thereby completing the circuit controlled by the switch. When the door is closed again 35 the initial travel of the latch 12 forces the plunger down, thereby rocking the lever 32 and placing the switch spring under tension at once. As soon the flange 29 has escaped the detent 39, which occurs early in 40 the inward travel of the latch, the switch is thrown into the "off" position, while the continued inward travel of the latch merely serves to further tension the return spring 45 42 and to again tension the switch spring in the "off" direction.

Various modifications of the invention will readily suggest themselves and I do not limit myself to the details shown, but claim as my invention—

50 1. A door switch comprising a push plate, a rock lever, a pin and slot connection between the same for rocking said lever, the slot being so angled that the pin travels inoperatively in one branch thereof, in combination with a switch lever, and a spring operatively connecting said rock lever to the switch lever, substantially as described.

2. A door switch comprising a push plate, a rock lever, a pin and slot connection between the same for rocking said lever, the slot being so angled that the pin travels inoperatively in one branch thereof, in combination with a switch lever, and a spring operatively connecting said rock lever to the

switch lever, together with a detent mechanism for releasing said switch lever with a snap action, substantially as described. 65

3. A door switch comprising a push plate, a rock lever, a pin and slot connection between the same for rocking said lever, the slot being so angled that the pin travels inoperatively in one branch thereof, in combination with a switch lever, and a spring operatively connecting said rock lever to the switch lever, together with a detent engaging lug on the switch lever and a detent on the push plate moving into and out of engagement with the lug on the switch lever during the travel of said push plate, substantially as described. 70 75

4. In a door switch, an operating latch, a switch operating push plate arranged beneath the same and an interposed pivoted member between said latch and push plate, for the purpose described. 80

5. In a door switch, an operating latch pivoted to the switch, a push plate vertically reciprocating beneath the same, a trigger pivoted to the push plate and engaging within the angle of the latch, for the purpose described. 85 90

6. In a door switch, a rock lever, a push plate actuated thereby, a plunger moving with said push plate and a coil spring surrounding the same to return said push plate after depression, together with a switch lever and an independent spring operatively connecting the same to the rock lever, substantially as described. 95

7. In a door switch, a rock lever with angled slot in one end thereof, in combination with a push plate having a pin engaging said slot throughout its length, but operative to swing said lever on its pivot during the engagement of said pin in only one branch of said slot, for the purpose described. 100 105

8. In a door switch, a push plate, a rock lever and a lost motion engagement between the same, for the purpose described, in combination with a switch lever, a spring connecting the same to said rock lever and a detent mechanism for insuring a snap action for the switch lever. 110

9. In a door switch, a push plate, a rock lever and a lost motion connection between the same, for the purpose described, in combination with a switch lever and means for actuating the same from the rock lever. 115

10. In a door switch, a push plate, a rock lever and means for operating the latter from the former during the initial inward and the final outward travel of said push plate, in combination with a switch lever, and an operative connection between the same and the rock lever, substantially as described. 120 125

11. In a door switch, a push plate, a rock

lever and means for operating the latter from the former during the initial inward and the final outward travel of said push plate, in combination with a switch lever, a 5 spring operatively connecting the same to the rock lever, together with a detent mechanism to insure a snap action for said switch lever.

In testimony whereof I have signed my name to this specification, in the presence of 10 two subscribing witnesses.

ERIC ANDERSON.
